UNITED STATES PATENT OFFICE

WALTER J. SCOTT, OF WOONSOCKET, RHODE ISLAND

STOP MOTION FOR DRAWING FRAMES

Application filed April 19, 1928. Serial No. 271,155.

This invention relates to an improved stop motion for drawing frames and has for its object to provide in such a stop motion an electric circuit controlled by a feeler member located between the draft rolls and the bobbin and on which the roving is wound whereby a building up of a surplusage of roving on the spindle will affect a movement of the circuit controlling member to stop the machine.

10 A further object of the invention is to locate one or more flexible circuit closing members at a point adjacent the upper end of the spindle so that if for any reason a surplus amount of roving led from the draft rolls is built up upon the spindle this surplus stock will cause action of said circuit closing members to stop the machine.

15 With these and other objects in view, the invention consists of certain novel features 20 of construction, as will be more fully described, and particularly pointed out in the appended claims.

In the accompanying drawings:

Figure 1 is an elevation partly in section 25 and illustrating my improved stop motion as applied to a drawing frame.

Figure 2 is an enlarged view partly in section illustrating the hollow upper portion of the spindle thru which the roving is fed 30 and the building up of the roving about the spindle to operate the circuit closing device.

Figure 3 is a view of the under side of one form of circuit closer.

Figure 4 is a section on line 4—4 of Figure 3.

Figure 5 is a section on line 5—5 of Figure 3.

Figure 6 is a section on line 6—6 of Figure 3.

40 Figure 7 is a side view partly in section illustrating the tripping mechanism for releasing the belt shift lever.

Figure 8 is a diagrammatic view showing the wiring diagram in connection with the 45 circuit closing member and the tripping

mechanism in the circuit for shifting the belt from the tight to the loose pulley.

It is found in practice that in operating drawing frames, more particularly worsted drawing frames, that after the stock is led 50 from the draft rolls down thru the hollow spindle to be laid by the flyer upon the traversing bobbin that in some instances, the bobbin does not drag sufficiently and so permits the roving to run ahead and become 55 slack to such an extent that it is wound about and bunched on the end of the spindle and also in other instances the roving becomes broken at some point intermediate the draft rolls and the point where it is wound onto 60 the bobbin, in which case the roving as it continues to be fed from the draft rolls is usually caught and wound about the upper end of the revolving spindle, sometimes above and sometimes below the spindle support or bearing 65 whereby considerable stock is wasted. To obviate this difficulty, I have mounted a so-called feeler member adjacent the upper end of the spindle at the point where it usually bunches about the spindle head, whereby this 70 bunching effect serves to operate the mechanism for stopping the machine; and the following is a detailed description of the present embodiment of my invention and showing one means by which these advantageous 75 results may be accomplished:

With reference to the drawings, 10 designates the draft rolls and 11 is the spindle which is rapidly revolved by the belt 12 from the pulley 13. The upper end of this type of 80 spindle is formed hollow, as best illustrated at 14, in Figure 2, and this upper end is provided with a bearing 15 in the rail 16.

Below this tubular portion of the spindle is mounted a guide eye 17 and a flyer 18 which 85 is provided with a guide 19.

From the draft rolls 10 the roving is led down thru the hollow portion of the spindle, thru the guide eye 17 and down thru the eye 19 in the flyer by which it is laid upon the 90

bobbin 21 which is mounted on the spindle. This bobbin rests upon the felt washer 22 carried by the traverse rail 23 so as to exert a friction on the bobbin to prevent it from a 5 too rapid rotation and to cause a certain amount of tension on the roving as laid thereon. This rail 23 is moved up and down by the rack 24 and pinion 25 to give the necessary traverse motion to the bobbin.

10 It is often found that the roving breaks down somewhere between the draft rolls and the point where it is laid upon the bobbin and in other instances it is found that the bobbin is not providing sufficient tension on the roving and in either of these cases the 15 loose portion of this roving is permitted to be wound about the rapidly travelling spindle and in most instances it will become wound about the upper end 26 of the spindle 20 head at the point *a* and in some instances it will also extend around beneath the bearing 15 and build up at the point *B* below the bearing.

25 In order to stop the machine when the roving begins to build up on this spindle, I have placed a circuit closing member 27 which I support upon this rail 16. This circuit closure is preferably provided with two flexible feeler fingers 28 which are herein shown as 30 being normally out of contact with their posts 29, and these posts 29 are connected together thru the connector 31 and are connected in the circuit thru the wires 32, the closing of which circuit energizes the solenoid magnet 33 to 35 withdraw the latch 34 and release the lever 35 which under action of the spring 36 moves the belt shift 37 to carry the belt from the tight pulley 38 to the loose pulley 39.

40 By this construction it will be seen that as soon as the roving breaks or becomes sufficiently loose it will build up about the upper end of the spindle that this built up portion of the roving engages one or both of these 45 feeler contact fingers 28 to press them into contact with terminal 29 to close the circuit and stop the machine.

45 I do not wish to be restricted to the use of an open electric circuit through which to stop the machine as in some instances a closed circuit may be employed for this purpose.

50 The foregoing description is directed solely towards the construction illustrated, but I desire it to be understood that I reserve the privilege of resorting to all the mechanical changes to which the device is susceptible, the invention being defined and limited only by the terms of the appended claims.

I claim:—

55 1. In a stop motion for drawing frames, a set of draft rolls, a hollow spindle thru which the roving is led to be laid upon the bobbin, a support for the upper end of said spindle, guiding means carried by the spindle for laying the roving onto the bobbin as fed from 60 said rolls, an electric circuit, a circuit con-

trol device carried by said spindle support having a flexible circuit control member whereby the building up of surplus roving on the spindle at a point adjacent said closure member will move the same to affect the circuit and stop the machine. 100

2. In a stop motion for drawing frames, a set of draft rolls, a roving package, a rotatable spindle, carrying means for laying the roving on the package, an upper support for the spindle thru which the upper end portion of the spindle extends, an electric circuit, circuit-control devices positioned both above and below said spindle support and arranged to be affected by the building up of 75 a surplusage of roving either above or below the support to stop the machine. 80

3. In a stop motion for drawing frames, a set of draft rolls, a hollow spindle thru which the roving is led to be laid upon the bobbin, a support for the upper end of said spindle, guiding means carried by the spindle for laying the roving onto the bobbin as fed from 85 said rolls, an electric circuit, a circuit control device carried by said spindle support having a contact member and a flexible arm both in 90 said circuit, said arm extending in a direction at a right angle to the axis of said spindle and normally spaced from said contact, whereby the building up of a surplusage of 95 roving on said spindle at a point adjacent said support will engage and move said arm into engagement with said contact to close the circuit and stop the machine. 100

4. In a stop motion for drawing frames, a set of draft rolls, a spindle, a rotatable member for laying the roving onto a bobbin as fed from said rolls, an electric circuit, and a flexible movable stop member laterally displaceable in relation to said spindle and spaced 105 therefrom and in position to be engaged and moved by building up of the roving radially on said spindle, to stop the machine. 110

5. In a stop motion for drawing frames, a set of draft rolls, a spindle having a head portion, a rotatable member for laying the roving onto a bobbin as fed from said rolls, an electric circuit, and a removable circuit closing feeler member laterally disposed in relation 115 to said spindle and spaced therefrom and in position to be engaged and moved by building up of the roving on said spindle head portion at either end thereof to close the circuit and stop the machine. 120

6. In a stop motion for drawing frames, a set of draft rolls, a spindle having a head portion and on which the winding bobbin is supported, a support for the upper end of the spindle adjacent the draft rolls, an electric 125 circuit, a movable circuit closure feeler member in said circuit laterally disposed in relation to said spindle and spaced therefrom to be engaged and moved to close the circuit and stop the machine by a building up of a sur- 130

plus of the material upon the lower end of the spindle head portion.

7. In a stop motion for drawing frames, a set of draft rolls, a hollow spindle through which the roving from said rolls is led to be wound upon a bobbin, a normally open electric circuit, a flexible circuit closure feeler member in said circuit laterally movable in relation to said spindle and spaced therefrom to be engaged and moved to close the circuit and stop the machine when a surplusage of the roving is built up radially upon the spindle adjacent its upper end.

In testimony whereof I affix my signature.

WALTER J. SCOTT.
